UNITED STATES PATENT OFFICE.

WILLIAM MASON, OF NEW HAVEN, CONNECTICUT, ASSIGNOR TO THE WINCHESTER REPEATING ARMS COMPANY, OF SAME PLACE.

SAFETY LOCKING DEVICE RELEASED BY RECOIL.

SPECIFICATION forming part of Letters Patent No. 585,392, dated June 29, 1897.

Application filed February 10, 1896. Serial No. 578,654. (No model.)

To all whom it may concern:

Be it known that I, WILLIAM MASON, of New Haven, in the county of New Haven and State of Connecticut, have invented a new 5 Improvement in Magazine-Firearms; and I do hereby declare the following, when taken in connection with the accompanying drawings and the letters of reference marked thereon, to be a full, clear, and exact description 10 of the same, and which said drawings constitute part of this specification, and represent, in—

Figure 1, an enlarged broken view, in side elevation, of the forward end of a gun-frame, 15 showing my improved handle-locking block applied thereto; Fig. 2, a similar but slightly less comprehensive view with the block and action-bar removed; Fig. 3, a cross-sectional view on the line *a b* of Fig. 1; Fig. 4, a detached view of the block, looking at the forward edge thereof; Fig. 4^a, a detached view of the block in inside elevation; Fig. 5, a reverse plan view of the block; Fig. 6, a broken view, in side elevation, of the gun, showing 20 the block in its closed position; Fig. 7, a plan view thereof; Fig. 8, a detached view, in side elevation, of the action-bar and the sleeve by means of which the same is connected with the sliding handle.

30 My invention relates to an improvement in that class of magazine-firearms in which the action mechanism is operated by a sliding handle located in front of it and constructed and arranged to move back and forth in a line parallel or substantially parallel with the gun-barrel, the object being to provide simple and reliable means for preventing the gun from being prematurely opened in the interval between the falling of the hammer and 35 the explosion of the cartridge by the exertion of a rearward draft on the part of the user upon the sliding handle.

With these ends in view my invention consists in the combination, with an action-bar, 45 of a handle-locking block coacting with the bar to lock the same in its closed position, and adapted to be thrown forward to unlock the bar by the recoil following the explosion of a cartridge in the gun-barrel.

50 My invention further consists in certain details of construction and combinations of

parts, as will be hereinafter described, and pointed out in the claims.

In carrying out my invention, as herein shown, I employ a block A, which for want 55 of a better term I shall call a "handle-locking block." This block is made heavier at its upper than at its lower end, whereby its upper end is virtually weighted, so that the block will act with force under the influence 60 of the recoil. At its lower end it is constructed with an inwardly-projecting trunnion A', adapted to enter a bearing-hole B, formed in the left-hand side wall of the gun-frame B', near the forward end thereof. The 65 said side wall of the gun-frame is constructed with a shallow recess B² for the reception of the body of the block and with a slot B³, located at the lower end of the said recess and intersecting at its bottom the opening B⁴, 70 formed in the gun-frame for the reception of the action-bar C, as clearly shown in Fig. 3. The said slot B³ receives and provides clearance for the locking-lug A², formed upon the inner face of the block.

75 A deep groove B⁵, having vertical side walls, leads out of the bottom of the recess B³ before mentioned and is provided for the reception of a retaining-flange A³, formed upon the lower face of the lug A² and designed to hold 80 the block against lateral movement without interfering with the freedom of its oscillating movement on its trunnion A'. The said lug A² locks the action-bar C in its closed position by entering a locking-notch C', Fig. 8, 85 formed in the rear end of the lower edge of the bar, the forward end of the said edge being constructed with a long clearance-notch C², the purpose of which will be described later on. The said bar is furnished upon the 90 outer face of its forward end with a horizontally-arranged resetting-finger C³, which enters a flaring pocket A⁴, formed to receive it in the forward edge of the block, whereby the block is positively swung from its open 95 position back into its closed position.

The action-bar C is connected at its forward end, as shown, with a sleeve C⁴, rigidly secured within the forward end of the sliding handle C⁵, mounted and sliding back and 100 forth upon the tubular magazine D in a line parallel or substantially parallel with the

longitudinal axis of the gun-barrel D', but the particular construction of the action-bar and its connection with the sliding handle and the mounting of the same are immaterial 5 and may be varied as desired.

The block is constructed with a deep hole A⁵, entering it from its upper end and formed for the reception of a yielding catch-pin E and the coiled spring E', provided for exerting a constant effort to throw the same outward, the said spring being located in the bottom of the hole A⁵. The said pin is constructed with a stop-notch e, receiving a stoppin e', which limits the longitudinal movement 10 of the pin. The outer end of the pin is beveled for coaction with a fixed retaining-pin F, set into the gun-frame B' in the upper portion of the recess B² before mentioned, and as shown in Fig. 2. The block is adapted to 15 clear this pin by its provision with a segmental clearance-slot A⁶, entering it from the upper portion of its forward edge and extending rearwardly, so as to intersect the upper portion of the hole A⁵, provided for the 20 reception of the yielding catch-pin E and the spring E' thereof. The extreme rear end of the action-bar is provided, as shown, with an operating-lug C⁵, which enters a path cam-slot G, Fig. 6, formed in the left-hand side 25 wall of the breech-closure locking-block G', which in this case has the function of transferring the cartridges from a point in rear of the tubular magazine to a point in rear of the gun-barrel.

30 It will be noticed by reference to Fig. 6 that when the gun is closed the lug C⁵ is sufficiently cleared from the rear wall of the inclined forward portion of the path cam-slot G to allow the action-bar, and hence the sliding handle, to be moved back and forth within 35 narrow limits without disturbing the said locking-block G'. This "lost motion" of the handle, as it may be called, permits that movement of the action-bar required for the 40 operation of the operating-block.

Having now described the construction in detail of my improved gun as herein shown, I will proceed to set forth the mode of its operation.

45 When the gun is fully closed, the parts occupy the positions in which they are shown in Fig. 6, the locking-block being held in its rearwardly-inclined closed position by means of the engagement of the beveled upper end 50 of the catch-pin with the rear face of the fixed pin under the influence of the spring E'. In this position of the handle-locking block its locking-lug A² is entered into the locking-notch C' of the action-bar, whereby the same, 55 and consequently the sliding handle, is firmly locked against rearward movement. It will thus be seen that if after the gun is closed the user thereof exerts an untimely rearward draft upon the sliding handle he cannot pre- 60 maturely open the gun in the interval between the falling of the hammer and the explosion of the cartridge, for the recoil following the

explosion of the cartridge is necessary to unlock the gun; but when the cartridge explodes and the recoil takes place the weighted 70 upper end of the handle-locking block is thrown forward against the tension of the spring E', which yields and permits the catch-pin to be shifted, so to speak, from engagement with the rear face of the fixed pin to 75 engagement with the forward face thereof, as shown in Fig. 1, which represents the handle-locking block as being held in its forward or open position by means of the engagement of the beveled outer end of the catch-pin with 80 the forward face of the fixed pin. When the block is thrown under the influence of the recoil, as set forth, from its rearwardly-inclined closed position to its open position, its locking-lug A² is forced downward out of the 85 locking-notch C' of the action-bar, which is thus unlocked and released for the rearward movement required for opening the gun. Then as the action-bar nears the limit of its 90 rearward movement its resetting-finger C³ enters the flaring pocket A⁴ of the handle-locking block and, engaging with the bottom of the said pocket, forces the block rearward into its closed position, causing the yielding catch-pin E to be snapped, so to speak, under 95 the fixed pin F and transferring the engagement of its beveled outer end from the front face of the pin to the rear face thereof. As the handle-locking block is thrown back from its open to its closed position its locking-lug 100 A² is lifted into the clearance-notch C². Now at the beginning of the closing movement of the gun the long inclined rear wall of the clearance-notch C² engages with the locking-lug of the operating-block, whereby the same 105 is slightly swung forward, but not sufficiently to shift its catch-spring from engagement with the rear face of the fixed pin to the forward face thereof. When, however, the action-bar reaches the limit of its closed position, the 110 spring E' of the catch-pin asserts itself, and by urging the beveled nose of the catch-pin 115 against the rear face of the fixed pin causes the block to be swung back into its fully-closed position, whereby its locking-lug is re-entered into the locking-notch of the action-bar, as before set forth.

It is apparent that in carrying out my invention some change from the construction herein shown and described may be made. I would therefore have it understood that I do not limit myself to such construction, but hold myself at liberty to make such changes and alterations as fairly fall within the spirit and scope of my invention.

Having fully described my invention, what I claim as new, and desire to secure by Letters Patent, is—

1. In a magazine-firearm, the combination with the frame and barrel thereof, of a sliding supporting and operating handle located forward of the frame and movable back and forth in a line parallel with the longitudinal axis of the barrel, an action-bar extending

rearwardly from the handle and adapted to be connected with the action mechanism of the arm, a handle-locking block pivotally connected at or near its lower end with the gun-frame upon the outer face of one of the side walls of the same and near the forward end thereof, and adapted to coact with the rear end of the bar and lock the gun closed, the said block being thrown forward to unlock the bar by the recoil following the explosion of a cartridge in the barrel and locking means mounted in the block for retaining the same in its rear or closed position and in its front or open position.

15 2. In a magazine-firearm, the combination with the frame and barrel thereof, of a sliding supporting and operating handle located forward of the frame, and movable back and forth in a line parallel with the longitudinal axis of the barrel, an action-bar extending rearwardly from the handle, and adapted to be connected with the action mechanism of the gun, a handle-locking block coacting with the said action-bar to lock the gun closed, and locking means mounted in the block for retaining the same in its rear or closed position, and in its front or open position.

30 3. In a magazine-firearm, the combination with the frame and barrel thereof, of a sliding supporting and operating handle located forward of the frame and movable back and forth in a line parallel with the longitudinal axis of the said barrel, an action-bar extending rearwardly from the handle and adapted to be connected with the action mechanism of the gun, a handle-locking block coacting with the said action-bar to lock the gun closed, pivotally connected at its lower end with one of the side walls of the gun-frame near the forward end thereof, and having an inward projection at a point above its pivot for coaction with the action-bar which reciprocates adjacent to its inner face, and locking means mounted in the block for retaining the same

45 in its rear or closed position and in its front or open position.

4. In a magazine-firearm, the combination with an action-bar, of a handle-locking block coacting with the same to lock it in its closed position, and constructed with a yielding catch-pin coacting with a fixed pin or projection on the frame to hold it in its rear or closed position, and in its front or open position, substantially as described.

5. In a magazine-firearm, the combination with an action-bar provided at its forward end with a resetting-finger, of a handle-locking block coacting with the bar to lock the same in its closed position, and adapted to be acted upon by the resetting-finger to be thrown back into its closed position, substantially as described.

6. In a magazine-firearm, the combination with the frame thereof, of an action-bar, and a handle-locking block coacting with the bar to lock the same in its closed position, pivotally connected at its lower end with the gun-frame, and constructed with a retaining-flange entering a slot in the frame and holding the block against lateral movement without interfering with its oscillating movement, substantially as described.

7. In a magazine-firearm, the combination with the action-bar thereof, of a handle-locking block pivotally connected at its lower end with the gun-frame, constructed with a locking-lug to coact with the bar for locking the same in its closed position, adapted to be acted upon by the bar for being shifted from its open to its closed position, and provided with a yielding catch-pin having its outer end beveled and coacting with a fixed pin on the frame for retaining the block in its open and closed positions, substantially as set forth.

In testimony whereof I have signed this specification in the presence of two subscribing witnesses.

WILLIAM MASON.
